G. W. HICKS.
RAILROAD TIE.
APPLICATION FILED FEB. 28, 1917.

Patented Dec. 25, 1917.

UNITED STATES PATENT OFFICE.

GUY W. HICKS, OF FALLS CREEK, PENNSYLVANIA.

RAILROAD-TIE.

1,251,229.

Specification of Letters Patent. Patented Dec. 25, 1917.

Application filed February 28, 1917. Serial No. 151,523.

To all whom it may concern:

Be it known that I, GUY W. HICKS, a citizen of the United States, residing at Falls Creek, in the county of Jefferson and State of Pennsylvania, have invented certain new and useful Improvements in Railroad-Ties, of which the following is a specification.

This invention relates to railroad-ties, and has for its object to provide cross ties for railway tracks having strength and durability and adapted to yieldably support the rails, take up and dissipate all shocks and jars incident to the movement of trains over the tracks, to permit free expansion and contraction of the rails, and prevent them from spreading or careening, and to maintain alinement and gage of track under all conditions.

With the above as the principal objects in view, the invention consists of the novel construction, combination and arrangement of parts hereinafter described, pointed out in the appended claims, and illustrated in the accompanying drawings, in which—

Figure 1 is a side elevation of a railroad-tie constructed in accordance with the present invention,

Fig. 2 is a top plan view of the same, Fig. 3 is a view of one end of the cross-tie,

Fig. 4 is a vertical longitudinal sectional view through one end of the cross tie taken on the line 4—4 of Fig. 3, and

Figs. 5 and 6 are perspective views of certain details of the invention.

In the drawings, 10 indicates the body of the tie having the usual proportions as to length, width, and height, and made preferably of concrete cement by casting the same in a mold in the usual manner. At the center of the tie is a depression 11 that extends to or nearly to the bottom of the tie and entirely across the same, the sides of the depression inclining upwardly and outwardly toward the ends as clearly shown in Fig. 1. The tie is strengthened and braced by a metal plate 12, preferably formed of steel that extends from end to end of the tie following the upper surface thereof and the sides and bottom of the depression 11. The plate 12 is about half the width of the tie and is seated in a groove in the center thereof, the top of the tie and the upper surface of the plate being in the same hori-

zontal plane. For the purpose of holding the plate 12 to the body of the tie, staples or yokes 13 extend across the plate and into the body of the tie through the top thereof and are rigidly held in place by the concrete. Similar staples 14 pass into the concrete over the plate 12 within the depression 11. These staples or yokes are preferably made of metal square in cross section with their ends twisted as at 15 to insure their retention in the concrete and to prevent them from being pulled out. The rails 16 which cross the tie rest upon the top thereof and upon the upper surface of the plate 12, being secured to said plate by outside clamps 17 and inside clamps 18 that overlap the base flanges of the rails and are secured by bolts 19 to the plate 12, said bolts passing through the plates to the under side thereof, the heads of the bolt projecting into openings 20 in the cross ties. The openings 20 in the ends of the cross-tie extend inwardly from the ends of the tie a short distance beyond the inner bolts 19 and are of such height and width as to readily permit the entrance of suitable tools for holding the heads of bolts 19 while the nuts thereon are tightened. Preferably the bottom and sides of each opening 20 have a slight inward taper to permit the core, by means of which they are formed, to be withdrawn after the tie has been cast and hardened.

To keep the clamps 17 and 18 from shifting or slipping away from the rails 16, their ends which rest upon the plate 12 are seated within pockets 21 on the upper surface of the plate formed by a shallow upstanding flange 22 surrounding the ends and two sides of each clamp, said flanges being integral with or secured to the top of the plate 12.

Extending across the top of the depression 11 in the tie 10 and riveted to the plate 12 at each edge of said depression is a resilient brace plate 23, preferably transversely corrugated as shown to increase its resiliency, but of such size and thickness as to securely connect the two ends of the tie across the top of the depression and hold said ends rigidly together under all the usual conditions that are met with, but which will yield when the tie is subjected to unusual conditions of pressure or strain.

In use, the ties are placed as usual upon

the ground and the space between the ties and also the depression 11 in each tie filled with ballast in the usual manner. The rails are secured to the ties by placing them across 5 the same between the pockets 21 and then bolting the clamps 17 and 18 over the bottom flanges of the rail to the metal plate 12 on the top of the tie, the openings 20 in the ends of the rails enabling the track layers 10 to insert a tool for holding the bolts immovable while tightening the nuts thereon. A tie of this character is strong and being 15 non-porous will resist water and may be used for an indefinite length of time; the rails are secured thereto to prevent spreading or overturning but will permit the molecular action 20 of expansion and contraction, due to changes in temperature. By means of the depression 11 in the center of the tie in connection with the resilient brace 23 a slight yielding will be permitted under unusual 25 conditions between the rails of the track.

What I claim is:

1. A railroad-tie comprising a body portion of cement concrete having a central depression extending across the body, a metal strengthening plate extending from end to end of the tie and following the contour of said depression, clamping means for securing 25 rails to said plate, and yokes or staples crossing said plate and seated in the body of the tie for holding the plate in place.
2. A railroad-tie comprising a body portion of cement concrete having a depression 30 in its center and extending across said body, a metal plate seated in the top of the tie body and extending from end to end thereof, said plate following the contour of said depression, clamping means for securing the 35 track rails to the metal plate, yokes or staples extending across the plate and seated in the body of the tie for holding the plate 40

in place, and a resilient plate connected at its ends to the first-named plate and extending across the depression in the tie. 45

3. A railroad-tie comprising a body made of cement concrete and having a V-shaped depression at the center thereof and extending across said body, an opening extending into the tie from each end, a metal plate 50 seated in the top of said tie in the plane of said top surface and extending from end to end of the tie, said plate following the contour of the V-shaped depression, yokes extending across said plate and having their 55 ends seated in the body of the tie for holding said plate in place, clamps securing the track rails upon the top of the tie, fastening bolts extending through said clamps and the plate into the openings formed in the ends 60 of the tie, and a resilient plate spanning the depression in the body of the tie and riveted at its ends to the first named plate.

4. A railroad tie comprising a body of cement concrete having a central V-shaped 65 depression extending across the same and an opening extending into the body of the tie at each end thereof, a metal plate extending from end to end of the tie in the longitudinal center thereof and following the contour 70 of the V-shaped depression, the top of the plate and the top of the body being in the same plane, clamping means for the track rails bolted on said plate and extending therethrough into the openings in the end 75 of the tie, and a spring plate extending across the top of the depression and riveted at its ends to the first-mentioned plate.

In testimony whereof I affix my signature in presence of two witnesses.

GUY W. HICKS.
